SINGLE ACTING PUMP

Edmund L. Fitch, Dayton, Ohio, assignor to The Dayton Steel Foundry Company, Dayton, Ohio, a corporation of Ohio

Application March 4, 1947, Serial No. 732,250

2 Claims. (Cl. 103—159)

The present invention has as its object the designing of a new form of single acting pump which will operate to discharge the fluid being pumped on the down stroke of the pump. The construction shown is simple, made of few parts and inexpensive to manufacture, yet is very efficient in its operation. As it utilizes the weight of the operator on the down stroke to force the fluid through the pump it is extremely easy to operate.

It is also an object of the invention to design a pump which can be readily adapted to different requirements, it being possible to adjust the pump to deliver relatively large volumes at low pressures or smaller volumes at higher pressures.

The best known and preferred form of the invention is shown and described, but it will be understood that the details of construction are not essential and may be varied within the scope of the appended claims.

In the drawings which show the pump in its perfected form:

Fig. 1 is a side elevation of the pump, the full lines showing the handle in an intermediate position, perpendicular to the axis of the pump, the extreme positions of the handle attained during pumping being indicated in broken lines.

Fig. 2 is a view looking at the front of the device.

Fig. 3 is a somewhat enlarged section on the line 3—3 of Fig. 2.

Fig. 4 is a perspective view taken at the fulcrum for the operating handle.

Fig. 5 is a view similar to Fig. 1, showing the handle in an adjusted position, axially of the slide mounting in its fulcrum pivot, and

Fig. 6 is a view similar to Fig. 5, showing the handle inserted in an alternative socket, and with the apparatus arranged for highest possible mechanical advantage.

The pump shown herein as the specific embodiment of the invention is intended to be mounted on the wall of a room or building, the framework of machinery or vehicle, or on some other permanent support. The pump is mounted between two parallel angular bracket members or arms 1, the ends of which are welded to upper and lower vertical base plates 2 and 3 which are provided with apertures 4 by which the pump assembly may be fixed to a support of requisite stability.

The angles or elbows of the bracket are somewhat enlarged as shown and at these points two aligned bushings 5 are welded in openings in the bracket. Near the upper end of the bracket is

located the transverse pivot pin 6 on which is pivoted the pump cylinder 10.

As shown in detail in Fig. 3, the pump cylinder is provided at its lower end with a fluid tight bushing 11 through which reciprocates the rod 12 carrying the piston head 13, both the rod and the piston head being suitably packed, preferably with standard O-rings, such as commonly used for such purposes.

10 In the wall of the cylinder below the piston head is tapped the inlet 15 and in the top of the cylinder is the outlet 16, the two pipes 15 and 16 being connected as shown, an adjustable by-pass valve 17 being located between the connections 15 and 16. Since the pump cylinder rocks about the pivot 6 during its operation the piping is connected to the inlet and outlet for the fluid by flexible hose as indicated.

In the head of the piston is located the valve 20 which communicates with the inlet side of the piston by the T-shaped passage 21 over which is located the spring held ball valve 22. An apertured plug 24 retains the valve on its seat. The head of the cylinder is provided 25 with the outlet passage 25 leading to the port 16 and in this passage is located the spring pressed ball valve 26.

To reciprocate the piston, the rod 12 is threaded at its lower end and at this point is attached the 30 yoke 30 in the lower end of which is located a pivot pin 31 on which is pivoted the end of an operating rod or lever 32 which extends to the right as shown in Fig. 1. The operating lever is 35 slidably received in a transverse passage 36 formed through the center of a heavy bearing sleeve 37 mounted for rotation in the bushings 5, the sleeve being held in position by snap rings 38 at either side of the bushings.

The slide fit between the rod 32 and the sleeve 40 37 permits the operator to vary the distance between the fulcrum and the point 31 to lengthen or shorten the work arm of the lever and the stroke of the piston and thereby adjust the pump for delivering fluid at the varying volumes and pressures. The pivot 6 permits the cylinder 10 to shift its position, in accordance with the adjusted position of lever 32. In the full lines in Fig. 1 the pump is shown as set for approximately the longest stroke of the piston.

45 Fixed to lever 32, as by a pin 40, is a dual socket member comprising divergent sleeves 41, 42, joined by a triangular web 43, each sleeve adapted to receive the handle 44, which may have a hand grip 46.

50 As seen in Fig. 1, lever 32 is perpendicular to

the axis of cylinder 10. In this position of adjustment, the inner end of sleeve 41 abuts fulcrum pivot sleeve 37. With the parts thus arranged perpendicularly, it is possible to swing the operating handle through an angle of about 15° on each side of the mean position without any sliding of lever 32 in its mounting. Larger angles of swing will seldom be necessary, but the lever may be locked in adjusted position, as by the set screw 47 in sleeve 37, seen in Fig. 4, if desired.

In Fig. 5, the lever 32 is shown adjusted outwardly to yield higher mechanical advantage. As in the case of Fig. 1, a mean position of the handle is assumed wherein lever 32 is perpendicular to the axis of cylinder 10. This position is easily found and maintained, for the maximum positions of the handle on either side of the mean are critical, and beyond these positions the lever slides suddenly. However, it is easy to maintain the lever within the critical range of swing.

The adjustment shown in Fig. 6 is employed for very high mechanical advantage. In this case the lever 32 is swung outward to a maximum, limiting position, with its inner end abutting fulcrum sleeve 37. Since outward sliding of rod 32 in this case is not possible, the sleeve 37 may be turned until lever 32 and cylinder 10 form an obtuse angle, and the pumping is occasioned by toggle action. In such an arrangement, the lever 32 is turned at a considerable angle below the horizontal, and it will therefore be convenient to insert handle 49 in auxiliary sleeve 42.

It will be seen that a very simple but very effective pump construction has been devised and that in all cases the operation of the pump on its delivery stroke is aided by the weight of the operator. It will also be seen that the pump is quickly adaptable for either high or low pressure delivery with corresponding changes in the volume delivered.

The pump may be used either as a hydraulic or pneumatic pump.

What is claimed is:

1. In a pump, a supporting structure, a fluid-pressure unit comprising cooperating piston and cylinder elements, one of which elements is pivotally attached to the supporting structure, a pivot rotatably carried in a portion of the supporting structure, and an operating lever having a straight portion received in said pivot for sliding adjustment with respect thereto, and said lever having one of its ends pivotally attached to the other of said elements.
2. In a pump, a supporting structure, a fluid-pressure unit comprising cooperating piston and cylinder elements, one of which elements is pivotally attached to the supporting structure, a pivot rotatably carried in a portion of the supporting structure, and an operating lever having a straight portion received in said pivot for adjustment with respect thereto in a direction transversely of the pivot axis, and said lever having one of its ends pivotally attached to the other of said elements.
